By his Attorney J.W. Ritter, Jr.

UNITED STATES PATENT OFFICE.

HENRY B. ROBISCHUNG, OF KALAMAZOO, MICHIGAN, ASSIGNOR TO THE CHICAGO RAILWAY EQUIPMENT COMPANY, OF CHICAGO, ILLINOIS.

STRUT FOR BRAKE-BEAMS.

SPECIFICATION forming part of Letters Patent No. 577,883, dated March 2, 1897.

Application filed March 21, 1896. Serial No. 584,300. (No model.)

To all whom it may concern:

Be it known that I, HENRY B. ROBISCHUNG, a citizen of the United States, residing at Kalamazoo, in the county of Kalamazoo, State of Michigan, have invented certain new and useful Improvements in Posts or Struts for Brake-Beams; and I hereby declare the following to be a full, clear, and exact description of the same, reference being had to the accompanying drawings, in which—

Figure 1 is a top plan view of a trussed brake-beam having a strut embodying my invention. Fig. 2 is a detached enlarged side view of the strut. Fig. 3 is a top plan view of the strut detached. Fig. 4 is a side view of the box or cage section of the strut, the detachable and reversible central or lever section being removed. Fig. 5 is a top plan view of the box or cage section of the strut shown in Fig. 4, the lever-section being removed. Fig. 6 is a detached view of the reversible central or lever section of the strut or post. Fig. 7 is a transverse section of the strut or post (cage and lever sections) on the line $x-x$. Fig. 3. Figs. 8 and 9 are side views of the strut or post, showing a modification in the means for securing the detachable reversible lever-section to the cage-section of the strut or post.

Like symbols refer to like parts wherever they occur.

My invention relates to the construction of struts or posts for brake-beams in general; but has been especially devised for use in the construction of trussed brake-beams, and therefore is herein shown in connection with a trussed brake-beam, though not intended to be limited thereto.

In service a brake-beam, whether a simple beam or a trussed beam structure, may necessarily be operated by either a right or left hand lever, according to the character and arrangement of the brake-rigging, and in the manufacture of the beam provision therefor has to be made, necessitating, under ordinary circumstances, the carrying in stock of numerous patterns and posts or struts for both right and left hand levers. In order to overcome this annoyance and expense, sectional rotatable posts or struts have heretofore been devised, some of which are objectionable, es-

pecially in trussed beams, as necessitating the letting down or dismembering of the truss where readjustment of the strut (from right to left, or vice versa) is required after the beam has been set up, and others are more or less objectionable owing to size, weight, and complication of structure, the latter an always undesirable feature in structures, like brake-beams, which are subjected to rough usage and are left in charge of unskilled labor.

The object of the present invention is to secure a simple and efficient reversible strut or post which in trussed beams can be changed from right to left, or vice versa, without dismembering the truss structure, and in any beam, whether trussed or otherwise, can be changed by unskilled labor without resort to the shop or to special tools.

To this end the main feature of my invention embraces the combination, in a post or strut for brake-beams, of an outer or cage section and an inner detachable reversible lever-section, and suitable means for securing the sections together.

There are other minor features of invention, all as will hereinafter more fully appear.

In the drawings, A indicates a beam of any desired construction, with which the lever-post B is connected in any approved manner. In the present instance, and for purposes of illustration only, the beam selected is a trussed beam wherein a tension rod or member C is combined with the beam A (compression member) and with the post (strut) B by the usual nuts c.

A post B embodying my invention may be constructed as follows, that is to say, of at least two sections, an outer or cage section and an inner or lever section, which when combined and secured are incapable of accidental displacement or of movement with relation to each other. The outer or cage section 1 or main casting may, for sake of saving weight, as well as to permit the passage of the brake-lever, be of slotted box form, that is to say, of general rectangular shape, composed of parallel side pieces or bars 2 2 and a bottom bar 3, connected at one end to a sleeve 4, in case of a tubular or cylindrical beam, or equivalent means for securing the post to the beam. The parallel bars 2 2 may

be perforated, as at 2^a 2^a, for the passage of bolts 10^a 10^a, by which the inner or detachable lever-section 7 is secured in position in the cage-section 1, and may be notched, as at 2^b, 5 to accommodate the end of the fulerum-pin of the brake-lever. The opposite ends of the parallel bars 2 2 and bottom bar 3 composing the cage B may be connected, and in case of a trussed beam should be provided with a 10 seat or notch 5 for the tension-rod C and a perforated lug or lugs 6 for the attachment of a third suspension-hanger.

7 indicates the removable and reversible included or lever section, which may be a casting 15 of dimensions corresponding with the interior of main casting or cage 1, preferably of general rectangular section with parallel bars 8 8, connected above and below and perforated, as at 9 9, for the lever pin or fulerum, 20 and at 10 10 for the passage of bolts 10^a 10^a or equivalent means for securing the lever-section to the box or cage section 1.

Whatever may be the general form of the cage and the lever-section the parallel bars 25 8 8, which support the fulerum-pin, will always be so located that the lever-slot 12 (see Fig. 7) formed thereby will be in a plane which intersects the beam at other than a right angle, and when the lever-section 7 is 30 in position in the cage-section 1 the lever-slot 12 thereof will, no matter whether arranged for a right or left hand lever, register with one or other of the lever-slots (constituted by the side bars 2 2 and bottom bar 3) of the 35 cage-section. Where, as in the present instance, the post or strut is of substantially rectangular cross-section, (see Fig. 7,) the slot 12 will occupy a diagonal position.

Instead of securing the included or lever 40 section 7 to the cage by bolts 10^a 10^a, one end of the cage (see Figs. 8 and 9) may be provided with an overhanging or projecting lip 13, under which one end of the lever-section 45 is entered, while the opposite end of the lever-section is secured to the cage by a single bolt 10^a, as in the construction shown in Figs. 1 to 6. When the overhang or lip 13 is used, it is preferably slightly rounded out to avoid lost motion when the lever-section is in its 50 seat.

The construction being substantially as hereinbefore pointed out, the lever-section 7

is inserted in the cage-section 1 with the lever-slot 12 in the desired plane to right or left, and said section is then secured to the 55 cage-section by the bolts 10^a 10^a or equivalent means. Thereafter when it is desired to change the strut or post from a right to a left hand lever-post, or vice versa, all that is necessary is to remove the bolts 10^a 10^a, with 60 draw the lever-section 7 from cage 1, turn it end for end, replace it in the cage, and again insert the bolts 10^a 10^a, all of which can be readily done without dismembering the beam (if a trussed beam) by unskilled labor, with 65 ordinary tools, and without resort to the shop.

Having thus described my invention, what I claim, and desire to secure by Letters Patent, is—

1. A post or strut for brake-beams, composed of a cage-section, and an included reversible lever-section, substantially as and for the purposes specified. 70

2. The combination in a post or strut for brake-beams, of a cage-section having parallel side bars and a bottom bar, and a detachable lever-section having parallel bars which form the lever-slot and are perforated for the reception of the fulerum or lever pin, substantially as and for the purposes specified. 75 80

3. The combination in a post or strut for brake-beams, of a slotted box or cage section and an included detachable and reversible lever-section having a lever-slot which registers with a slot of the cage-section, substantially as and for the purposes specified. 85

4. A post or strut for brake-beams, composed of a box or cage section and an included detachable lever-section, said sections being substantially rectangular in cross-section, the included section having a diagonally-placed lever-slot, and the cage-section having a slot which registers with the diagonally-placed slot of the included lever-section; substantially as and for the purposes 90 95 specified.

In testimony whereof I affix my signature, in presence of two witnesses, this 19th day of March, 1896.

HENRY B. ROBISCHUNG.
